[57] CLAIM

The ornamental design for a water purifier, as shown and described.

DESCRIPTION

FIG. 1 is a front elevational view of a water purifier, showing my new design,

FIG. 2 is a rear elevational view thereof,

FIG. 3 is a side elevational view thereof,

FIG. 4 is an elevational view taken from the side opposite that shown in FIG. 3;

FIG. 5 is a top plan view thereof,

FIG. 6 is a bottom plan view thereof,

FIG. 7 is a perspective view taken from the top, front and right side thereof;

FIG. 8 is another perspective view taken from the top, front and right side thereof, showing the water purifier in an open position; and

FIG. 9 is an exploded front perspective view thereof.

FIG. 2

FIG. 1

FIG.4

FIG.3

FIG. 5

FIG. 6

FIG. 8FIG. 7FIG. 9

UNITED STATES PATENT AND TRADEMARK OFFICE
CERTIFICATE OF CORRECTION

PATENT NO. : Des. 267,032
DATED : Nov. 23, 1982
INVENTOR(S) : Pierre LAFONTAINE

It is certified that error appears in the above-identified patent and that said Letters Patent is hereby corrected as shown below:

ON THE TITLE PAGE, ITEM 130 Foreign Application Priority Data, change "Oct. 10, 1979" to --Oct. 1, 1979--.

Signed and Sealed this

First Day of March 1983

[SEAL]

Attest:

GERALD J. MOSSINGHOFF
